UNITED STATES PATENT OFFICE.

DANA L. STEARNS, OF MARTELLE, IOWA.

VEHICLE JACK AND LIFTER.

No. 923,454.

Specification of Letters Patent.

Patented June 1, 1909.

Application filed December 29, 1908. Serial No. 469,823.

To all whom it may concern:

Be it known that I, DANA L. STEARNS, residing at Martelle, in the county of Jones and State of Iowa, have invented a new and Improved Vehicle Jack and Lifter, of which the following is a specification.

This invention is in the nature of an improved construction of supporting means for lifting and sustaining motor vehicles and it primarily has for its object to provide an apparatus of this character of a simple, economical and durable construction and particularly designed so that under one adjustment thereof the vehicle can travel over it and under another adjustment it effectively raises the vehicle bodily and jacks it to hold it supported by its axles resting thereon and in position for conveniently lubricating the bearings, making repairs and for other purposes and also in such manner that the vehicle can be readily moved about in the garage or other places of storage.

With other objects in view that will be hereinafter fully explained my invention comprehends a suitable portable base or frame, lifting means mounted thereon, foldable down against the base under one adjustment, vertically movable to engage the under side of the vehicle axles or body and devices that coöperate with the frame and the lifting means for uniformly raising and lowering the said means, operable by a single crank member.

In its more complete nature, my invention consists in certain details of construction and novel arrangement of parts, hereinafter described, specifically pointed out in the appended claims and illustrated in the accompanying drawings in which:

Figure 1, is a top plan view of my invention the lifter beams being in their elevated positions. Fig. 2, is a longitudinal section thereof, the parts being as in Fig. 1, and horizontal axles and wheels of a motor vehicle being shown in dotted lines. Fig. 3, is a similar view, the lifter beams being at their lowermost position and the pinion conveying frame being lowered, to allow the vehicle to pass. Fig. 4, is an enlarged longitudinal section of the crank gear and adjusting screw sleeve and rod. Fig. 5, is an enlarged detail perspective view of an end of the pinion carrying support and its latching means. Fig. 6, is a perspective view of one toggle connection for the lifter beams. Fig. 7, is a perspective view of one of the lifter beams.

Fig. 8, is a detail view of one of the jack blocks hereinafter referred to.

In the practical construction, my invention comprises a main frame 4 preferably of rectangular shape and which may be of hard wood but is preferably of angle iron as shown, it having a suitable number of caster wheels 13, secured on the under side so the frame with the object supported thereon may be easily moved about the garage.

Upon the upper side of the side bars 40—40 of the frame 4 are secured brackets 3—3 arranged in sets, four sets being shown, in each set of which are mounted the pivot pins 30 on the lower ends of the toggle legs 12^a—12^a that coöperate with mates 12 that are pivotally connected at the inner ends to the legs 12^a by the joint pins 5—5 and whose outer and lower ends have stud bolts 2, each of which carries a friction roller 18, as clearly shown in Figs. 2 and 6, by reference to which it will be also noticed that the legs 12 of each set of toggle legs are joined by a rod 6, the ends of which join with the bolts 2, the forward set of bolts 2 also forming the connecting means for the inner ends of an A-shaped pull frame 7 that has a forwardly projected central pull rod 8 for the purposes presently explained.

1—1 designate a pair of oppositely disposed and longitudinally extended lift beams, preferably U-shaped channel iron, provided at the front and rear ends with a series of vertically disposed apertures 1^a—1^a for receiving the upper toggle joint bolts 5—5 as best shown in Fig. 7, a series of said apertures 1^a—1^a being provided so the beams 1—1 may be readily adjusted vertically to bring them to a proper height to suit different heights of vehicle axles.

So far as described, it is apparent that when the beams are at their lowermost position they lie flatwise on the base frame 4 and the latter being on the floor, as it were, the vehicle can readily be driven over the frame and the beams being in the position shown in Fig. 3, and when in such position the front and rear axles of the vehicle will be transversely over the beams 1—1 and the latter can be lifted together and uniformly by pulling the rod 8 in the direction indicated by the arrow x, it being understood the beams 1—1 will engage the axles and raise them as they are further lifted by suitable force.

For conveniently, quickly and effectively

moving the rod 8 forwardly and backwardly and at the same time provide for holding it to its longitudinally adjusted positions, I employ the means best shown in Fig. 4, by reference to which it will be seen the threaded end of rod 8 engages a long internally threaded sleeve 10 integrally or otherwise fixedly formed on the back of the large cog wheel 14 that also has a shoulder 22 for engaging the bearing block 90 that rises from a casting 9 bolted to the front cross member 42 of the frame 4 and in which the sleeve 10 is rotatably mounted.

Coacting with the cog wheel 14 is a smaller cog gear 16 journaled in a bearing 17^a formed on the upper end of an arched support 17 pivotally connected at the lower end as at 17^b—17^b to the frame 4, such connection being provided so that the wheel 16 and the support can be swung down as indicated in Fig. 3, that the wheel 16 and the arched member 17 will be out of the way and not interfere with a low body motor vehicle in driving the same over the elevating and supporting apparatus.

Wheel 16 has a crank handle 15 for turning it and the frame 17 has a latch member 17^d for holding it to its elevated position which is tripped when it is desired to lower the arch 17 and the wheel 16.

26 designates jack blocks that straddle the lifter beams where they engage the axles and these in practice may be of any thickness to adapt the jack for any height or length of machine.

From the foregoing, taken in connection with the accompanying drawings the complete construction, the operation and the advantages of my invention will be readily apparent.

It will be understood that the beams when down, lie flat on the bottom frame 4 and thus make it convenient to drive the machine over the beams, and when the axles are over the beams 1—1, the latter, by simply turning the crank 15, the gears 16 and 14 being in mesh, extend the toggle levers vertically which raises the beams 1—1 to engage the underside of the vehicle axles, which are 50 "jacked up" as it were, by a uniform movement of the beams under a screw feed and are held to their adjustment without the necessity of providing special means for holding the beams locked to their different positions.

By using my apparatus the motor vehicle can be held elevated when not in use, with its wheels off the ground and thus save the wear and strain on the tires, incident in having the weight of the machine thereon when standing in the garage and further, by holding the vehicle in the manner stated it can be moved around sidewise and endwise to admit of easy access to all the parts and the 65 convenient oiling, cleaning or adjusting

thereof, it being understood that the operation of raising, lowering and locking the beams to their adjustments is effected by the turning of the crank 15 as the screw feed devices shown and described effects the movement and locking of the beams.

Having thus described my invention, what I claim and desire to secure by Letters Patent, is:—

1. The combination with a portable frame, of two or more sets of oppositely disposed toggle levers at each side of the frame, each set of levers having the free end of one member pivotally connected to the frame and the free end of the other member slidable on the frame, the slidable members at each side being linked together, a lifting beam mounted on the toggle joints of each set of levers at each side, and a means mounted on the main frame connected with the toggle levers for 75 extending or contracting the toggle levers and locking them to their adjusted positions.

2. The combination with a portable frame, of two or more sets of oppositely disposed toggle levers, at each side of the frame, each set of levers having the free end of one member pivotally connected to the frame and the free end of the other member slidable on the frame, the slidable members of each side being linked together, a lifting beam adjustably mounted on the toggle joints of each set of levers at each side and a means mounted on the main frame connected with the toggle levers for 90 extending and contracting the toggle levers and locking them to their adjusted positions.

3. An apparatus of the character described, comprising in combination with a portable platform, a plurality of oppositely disposed sets of toggle levers, a lifter beam mounted on the fulcrums of the said toggle levers, one lever of each set of toggle levers being pivotally secured to the platform, the corresponding end of the other toggle lever 105 being slidable on the platform, means for coupling the slidable members of the toggle levers, a rod for shifting the said lever connecting members and another means for 110 pulling the said rod backward and forward and locking the same to its adjusted positions.

4. In an apparatus of the character described, the combination with the base frame, of toggle levers mounted on the base frame 120 in oppositely disposed pairs, lifter beams, mounted on the fulcrums of the toggle levers, means for extending and contracting the toggle levers, said means including a pull rod having a threaded end, an internally threaded sleeve rotatably mounted on one end of the main frame and adapted to receive the threaded end of the pull rod, and means 125 for rotating the sleeve.

5. In an apparatus of the character de-

scribed, the combination with the base frame, of toggle levers mounted on the base frame in oppositely disposed pairs, lifter beams mounted on fulcrums of the toggle levers, 5 means for extending and contracting the toggle levers, said means including a pull rod having a threaded end, a longitudinally threaded sleeve rotatably mounted on one end of the main frame and adapted to receive the threaded end of the pull rod and 10 means for rotating the sleeve, said means

consisting of a gear on the sleeve, an arched member pivotally mounted on the platform, a smaller gear mounted on the said arched frame adapted when the frame is swung up to 15 engage the gear on the sleeve and means for turning the small gear, all being arranged substantially as shown and described.
